SHIRT

Elvert Curtis, Gamaliel, Ky., assignor to Washington Manufacturing Company, Nashville, Tenn., a corporation of Tennessee

Filed Jan. 23, 1963, Ser. No. 73,285

Term of patent 14 years

(Cl. D3—25)

Fig. 1.

Fig. 2.

Fig. 3.

The dominant features of my design reside in the contrasting vertical bands sewn to each of the front breast pockets together with the button down tab all as shown in solid lines on the drawing.

I claim:

The ornamental design for a shirt, as shown and described.
